ARCH FOR BOILER FIREBOXES

Application filed October 6, 1931. Serial No. 567,181.

This invention relates to improvements in a baffle or screen which divides the interior of the boiler firebox of a locomotive into a combustion chamber and a furnace chamber and is known as the "brick arch". Important objects of the invention are, to provide such an arch of generally improved construction; to provide an arch of great durability; to provide an arch having improved supports for the bricks rendering it possible to employ durable metal bricks in place of the usual refractory bricks which disintegrate, and to provide for a desirably close arrangement of the water tubes in the arch structure and at the same time afford adequate communication between the firebox chambers for the flow of hot gases, and adequate clearance to permit workmen to enter the furnace chamber of the firebox from the combustion chamber.

In the drawings,

Fig. 1 is a section taken on the line 1—1 of Fig. 2 showing the improved brick arch in plan, a number of the bricks being removed;

Fig. 2 a vertical longitudinal sectional view of the firebox end of a locomotive boiler and the improved brick arch in the firebox;

Fig. 3 an elevation of the firebox end of the boiler;

Fig. 4 a detail perspective view of one of the arch bricks;

Fig. 5 an enlarged detail section taken on the line 5—5 of Fig. 2;

Fig. 6 a view similar to Fig. 1, showing a modified form of the arch;

Fig. 7 a vertical section taken on the line 7—7 of Fig. 6;

Fig. 8 an elevation of the firebox end of the boiler having the modified arch; and

Fig. 9 an enlarged detail section taken on the line 9—9 of Fig. 7.

The improved arch is shown embodied in a locomotive boiler of conventional form. The firebox space of the boiler is defined by the crown sheet 1, the back sheet 2, the back tube sheet 3, the inclined inside throat sheet 4, and the grate 5. A water jacket around the firebox is defined by the roof sheet 6, the

back head 7 and the outer throat sheet 8. The jacket space is an extension of the water space within the boiler shell 4. The fire door hole 10 is formed in the back sheet 2 and back head 7, and the boiler flues or tubes 11 extend from the tube sheet 3.

The arch is a screen or baffle extending from the back sheet 2 downward and rearward to the throat sheet 4 and dividing the firebox into a furnace chamber 12 and a combustion chamber 13 into which the flues 11 open. The purpose of the arch is to promote combustion, force the flames to impinge the back surfaces of the fire box, baffle sparks, abate smoke and protect the flues. Referring first to the form of my invention shown in Figs. 1 to 5 inclusive, the improved arch structure includes a series of inclined water-tubes 14 joined at their rear ends to the back sheet 2 and extending downward and forward to the inner throat sheet 4 to which their forward ends are joined. The ends of the tubes open through said sheets into the adjacent front and rear water jacket spaces, and provide for a circulation of the boiler water through the firebox. The tubes have spaced parallel forward reaches 14^a disposed in the same inclined plane and the forward ends of said reaches are joined to the throat sheet 4 on a horizontal line. These parallel tube reaches are of material length and they serve to support the arch bricks 15 which close the spaces between said tube reaches. At their rear ends the tubes have reaches 14^b which are diverted from the courses of said parallel reaches in a manner to provide adequate communicating space between the firebox chambers 12 and 13. The tubes form a plurality of groups and in each group the tubes are bent, as shown at 16, to converge their reaches 14^b laterally, diverge them vertically and dispose their rear ends in superposed positions. These ends, where they are joined to the sheet 2, lie in a fore-and-aft vertical plane. The back head 7 has apertures registering with said tube ends and closed by screw plugs 17, and the outer throat sheet 8 has apertures registering with the forward ends of the tubes and closed by screw plugs 18.

My improved arrangement of the arch tubes enables me to employ a greater number of tubes spaced more closely together with a consequent greater volume of water exposed to the heat in the firebox, and also permits the use of metal arch bricks instead of the usual bricks of refractory material. Heretofore the arch tubes of locomotive fireboxes have extended their full length with no lateral bend. Back of the arch bricks there must be sufficient space between the tubes for unrestricted flow of the hot gases from the furnace chamber to the combustion chamber. The spaces between the tubes must also be sufficient to admit a workman from the furnace chamber to the combustion chamber for cleaning and repairing work. This heretofore necessitated placing of the tubes quite a material distance apart, the lateral space between tubes being usually about sixteen inches. With the tubes so spaced it is impracticable to employ metal bricks because the large area of the bricks exposed between the tubes to the heat, and the limited cooling contact of the bricks with the tubes causes the bricks to fuse. Therefore it was necessary to employ the refractory bricks. These bricks are costly and they disintegrate rapidly. They must be removed frequently on account of work done in the firebox and in their removal they are generally broken and cannot be used again.

In my improved arch tube arrangement, wherein the rear end portions of the tubes are laterally bent out of the way for the required working and circulation clearance, I employ arch tubes of preferably about three inches outside diameter and have the brick supporting reaches of the tubes laterally spaced apart a distance approximately equal to the tube diameter. This arrangement adds materially to the number of tubes and enables the use of very narrow metal bricks, with materially increased cooling contact with the tubes. It will be understood, however, that the diameter and spacing of the tubing may be varied. I have also devised metal bricks 15 of improved design for mounting upon the tubes 14. As shown, each brick has outwardly and upwardly curved side flanges 15^a having concave under surfaces 15^b which fit closely around approximately one fourth of the tube circumference. Between the said flanges the brick has a depressed body portion 15^c which is interposed directly between the adjacent supporting tubes. The brick is approximately the same thickness throughout. The brick is thus designed for direct and rapid transference of its heat to the water tubes to prevent it from fusing. This brick design may be varied, however. The metal bricks will last indefinitely and may be repeatedly removed and replaced without injury. The close spacing of the tubes, with increased brick

cooling effect, also makes it possible to employ cheap, low temperature bricks of either refractory material or metal, if desired, for economical reasons. Also, the increased number of arch tubes, and the consequently increased volume of water exposed to the heat in the firebox adds materially to the efficiency of the boiler. Furthermore, the close spacing of the arch tubes causes a more even longitudinal water flow in the boiler, as it enables the water in the boiler to reach the tubes with less transverse flow.

Because of the close arrangement of the forward brick-supporting reaches 14^a of the tubes and the use of the short arch brick I provide a strong working platform on which the workmen may stand while cleaning the boiler tubes. This working platform extends from the throat sheet 4 forward and upward so that the workman has ample space and support while working on the boiler tubes. The bricks are of such shape that any stress brought on them by reason of the weight of the workmen is to a certain extent transmitted laterally to the tubes and to the bricks between the tubes. The short bricks will no be in any way injured by the workmen.

The ordinary locomotive fire box arch formed of refractory brick must be removed before the workmen can clean the boiler tubes. These bricks are usually quite large, approximately 16 inches in length, and the removal and replacement of them is expensive and frequently results in considerable breakage. With my metal brick and closely arranged tubes in the fire arch portion of the tubes the bricks need not be removed and are not in any way injured by the workmen while standing on them during the tube cleaning operation. The expense of the removal of the arch brick for the cleaning operation is saved, and also the expense of breakage of the brick which is usually consequent upon the cleaning and replacement of the ordinary refractory brick is avoided.

In the form of my invention shown in Figs. 6 to 9 inclusive the arch bricks are dispensed with and the tubes 14 alone are arranged to form the baffle. An increased number of tubes are employed and the parallel reaches 14^a of the tubes are disposed in close side to side contact to form a closed baffle. Otherwise the arrangement of the tubes is similar to that previously described. The rearward reaches 14^b and the forward ends of the tubes are preferably swaged down to a reduced diameter to separate the tubes at their joints with the firebox sheets 2 and 3 and give adequate strength to said sheets between the tube joints. The increased number of tubes adds still more to the efficiency of the boiler in addition to dispensing with the bricks and avoiding the labor of setting them up and removing them.

Instead of an increased number of tubes to form the baffle, tubes of greater diameter may be employed. In both forms of the invention the curvature of the tube reaches 14^b 5 is such as to permit the tubes to be easily cleaned.

What I claim is:

1. In a locomotive boiler firebox, a baffle arch structure dividing the firebox into a combustion chamber and a furnace chamber and comprising a series of water tubes having spaced parallel brick-supporting reaches and reaches laterally converged and disposed in superposed positions to provide increased 15 communicating space between said combustion chamber and furnace chamber; and bricks supported by said parallel reaches of the tubes and closing the spaces therebetween.
2. In a locomotive boiler firebox, a baffle arch structure dividing the firebox into a combustion chamber and a furnace chamber and comprising a series of water tubes having spaced parallel brick-supporting reaches 25 and reaches laterally converged and disposed in superposed positions to provide increased communicating space between said combustion chamber and furnace chamber; and metal bricks supported by said parallel reaches of the tubes and closing the spaces therebetween.

3. In a locomotive boiler firebox, a baffle arch structure dividing the firebox into a combustion chamber and a furnace chamber and comprising a series of fore-and-aft extending water tubes having spaced parallel brick-supporting reaches and rear end reaches laterally converged and disposed in superposed positions to provide increased 35 communicating space between said combustion chamber and furnace chamber; and bricks supported by said parallel reaches of the tubes and closing the spaces therebetween.

4. In a locomotive boiler firebox, a baffle arch structure dividing the firebox into a combustion and a furnace chamber and comprising a series of fore-and-aft extending water tubes having spaced parallel brick-supporting reaches laterally spaced apart a 45 distance approximately equal to the outer diameter of the tubes, and rear end reaches converged laterally and disposed in superposed positions to provide increased communicating space between said combustion 50 chamber and furnace chamber; and bricks supported by said parallel tube reaches and closing the spaces therebetween.

5. In a locomotive boiler firebox, a baffle arch structure dividing the firebox into a combustion chamber and a furnace chamber and comprising a series of fore-and-aft extending water tubes having spaced parallel brick-supporting reaches laterally spaced apart a 60 distance approximately equal to the outer diameter of the tubes, and rear end reaches

converged laterally and disposed in superposed positions to provide increased communicating space between said combustion chamber and furnace chamber; and bricks supported by said parallel tube reaches and closing the spaces therebetween, said bricks having concave opposite edges fitting around the supporting tubes and an intermediate body portion disposed directly between adjacent tubes.

6. In a locomotive firebox having a water jacket in communication with the water space of the boiler, a baffle arch structure dividing the firebox into a combustion chamber and a furnace chamber and comprising a series of fore-and-aft extending water tubes 80 communicating at their opposite ends with the water jacket and forming part of the boiler water circulation system and having spaced parallel brick-supporting forward reaches, adjacent groups of said tubes having rear end reaches laterally bent and converged in each group and disposed in superposed positions in a fore-and-aft vertical plane passing through one unbent tube of the group and parallel with vertical planes passing through the forward reaches of the tubes of said group to provide material communicating space between said chambers; and bricks supported by said forward parallel 90 tube reaches.

7. In a locomotive firebox having a water jacket in communication with the water space of the boiler and having a back sheet and a throat sheet, a baffle structure dividing the fire box into a combustion chamber and a furnace chamber, and comprising a series of fore-and-aft extending water tubes supported at their forward ends in the throat sheet 100 and extending upwardly and rearwardly and connected at their rear ends to the back sheet above the fire door opening and forming part of the boiler water circulation system, said tubes having parallel brick supporting forward reaches arranged with slight spaces between them, adjacent groups of said tubes having rear end reaches laterally converging in each group to dispose the said rear portions in a fore-and-aft vertical plane parallel 105 with vertical planes passing through the forward reaches of the tubes of said group, whereby the transverse spaces between the superposed rear portions of the tubes of adjacent groups will be equal to the space between the central tube of one group and the central tube of the adjacent group, at the throat sheet; and metal bricks supported by the forward brick supporting reaches of said tubes, 115

said bricks forming a fire arch and a work platform extending from the throat sheet rearwardly and upwardly.

8. In a locomotive fire box having a water jacket in communication with the water space of the boiler and having a back sheet and a throat sheet, a baffle structure dividing the 120

- fire box into a combustion chamber and a furnace chamber, and comprising a series of fore-and-aft extending water tubes supported at their forward ends in the throat sheet and extending upwardly and rearwardly and connected at their rear ends to the back sheet above the fire door opening and forming part of the boiler water circulation system, said tubes having parallel brick supporting forward reaches arranged with slight spaces between them, adjacent groups of said tubes having rear end reaches laterally bent in each group to dispose the said rear portions in a fore-and-aft vertical plane passing through one unbent tube of the group and parallel with vertical planes passing through the forward reaches of the tubes of said group, whereby the transverse spaces between the superposed rear portions of the tubes of adjacent groups will be equal to the space between the unbent tube of one group and the unbent tube of the adjacent group at the throat sheet; and short bricks supported by the forward brick supporting reaches of said tubes, said bricks forming a fire arch and a work platform extending from the throat sheet rearwardly and upwardly.
9. In a locomotive fire box having a water jacket in communication with the water space of the boiler and having a back sheet and a throat sheet, a baffle arch and working platform structure dividing the fire box into a combustion chamber and a furnace chamber, and comprising a series of fore-and-aft extending water tubes supported at their forward ends in the throat sheet and extending upwardly and rearwardly and connected at their rear ends to the back sheet above the fire door opening and forming part of the boiler water circulation system, said tubes having parallel brick supporting forward reaches arranged with slight spaces between them, adjacent groups of said tubes having rear end reaches laterally bent in each group to dispose the said rear portions in a fore-and-aft vertical plane passing through one unbent tube of the group and parallel with vertical planes passing through the forward reaches of the tubes of said group, whereby the transverse spaces between the superposed rear portions of the tubes of adjacent groups will be equal to the space between the unbent tube of one group and the unbent tube of the adjacent group at the throat sheet; and short bricks supported by the forward brick supporting reaches of said tubes, said bricks forming a fire arch and a work platform extending from the throat sheet rearwardly and upwardly.
10. In a locomotive fire box having a water jacket in communication with the water space of the boiler and having a back sheet and a throat sheet, a baffle structure dividing the fire box into a combustion chamber and a furnace chamber, and comprising a series of fore-and-aft extending water tubes supported at their forward ends in the throat sheet and extending upwardly and rearwardly and connected at their rear ends to the back sheet above the fire door opening and forming part of the boiler water circulation system, said tubes having parallel brick supporting forward reaches arranged with slight spaces between them, adjacent groups of said tubes having rear end reaches laterally bent in each group to dispose the said rear portions of each group in a fore-and-aft compact group, whereby the transverse spaces between said adjoining compact groups will be greater than the spaces between the tubes at the throat sheet, and bricks supported by the forward brick supporting reaches of said tubes, said bricks forming a fire arch and a work platform extending rearwardly and upwardly.
11. In a locomotive fire box having a water jacket in communication with the water space of the boiler and having a back sheet and a throat sheet, a baffle structure dividing the fire box into a combustion chamber and a furnace chamber, and comprising a series of fore-and-aft extending water tubes supported at their forward ends in the throat sheet and extending upwardly and rearwardly and connected at their rear ends to the back sheet above the fire door opening and forming part of the boiler water circulation system, said tubes having parallel forward reaches arranged close together to form the fire arch portion of said tubes, adjacent groups of said tubes having rear end reaches laterally bent in each group to dispose the said rear portions of each group in a fore-and-aft compact group, whereby the transverse spaces between said adjoining compact groups will permit a workman to pass therethrough and the said closely-arranged forward reaches of said tubes will serve as a support for the workman while cleaning the boiler tubes.

ROBERT J. NEEDHAM.
